Primary Examiner — Holly H Baynam(74) *Attorney, Agent, or Firm* — Daniel W. Sullivan(57) **CLAIM**

The ornamental design for a golf bag hip pad, as shown and described.

DESCRIPTION

FIG. 1 is a perspective view of the golf bag hip pad of this invention;

FIG. 2 is a first side view of the golf bag hip pad of this invention;

FIG. 3 is a rear view of the golf bag hip pad of this invention;

FIG. 4 is a second side view of the golf bag hip pad of this invention;

FIG. 5 is a front view of the golf bag hip pad of this invention; and,

FIG. 6 is a top plan view of the golf bag hip pad of this invention.

In FIGS. 1-6, the broken lines depict unclaimed portions of the golf bag. The heavier dash lines shown in the views of the golf bag hip pads are representative of stitching that forms part of the claimed design.
